UNITED STATES PATENT OFFICE.

DAVID SARASON, OF BERLIN, GERMANY.

BANDAGE AND THE LIKE.

No. 919,250.

Specification of Letters Patent. Patented April 20, 1909.

Application filed June 25, 1908. Serial No. 440,351.

To all whom it may concern:

Be it known that I, DAVID SARASON, a subject of the German Emperor, residing at Berlin, German Empire, have invented certain new and useful Improvements in Bandages and the Like, of which the following is a specification.

My invention relates to improvements in so-called hydropathic or wet bandages or compresses. Ordinarily in making such applications a linen or other cloth wrung out in water is wrapped round or laid upon the part of the body to be treated and a woolen or like wrapper then bound over it. A serious defect of this method is, however, that owing to the outer wrapper being separated from the skin of the patient by the wet inner cloth, it does not lie close at the edges, so that air readily gets access to the wet cloth. A further disadvantage is that the wrapper and cloth are very liable to shift their position relatively to each other, with the result that the cloth becomes more or less exposed. In either case the risk of the patient taking a chill is very great.

The object of my invention is to obviate these drawbacks and my invention consists in the improved bandage hereinafter fully described and afterward specifically claimed.

Two forms of bandage made according to my invention are shown by way of example in the accompanying drawing.

Figure 1 is a plan of a bandage in which the wrapper edges are adapted to be folded down upon the wet cloth. Fig. 2 is a plan of a modification, in which the wrapper is furnished with thickened edges.

Referring to Fig. 1, the edges a^1 of the outer wrapper a are stiffened in any suitable manner, such as by means of tinfoil or other desirable material, which while being readily pliable is sufficiently strong and not resilient. This may be done in the manner shown in the drawing, transverse tongues of tinfoil b being attached to the marginal portions of the wrapper a , as can be clearly seen at 1. In employing the bandage the wrapper a is spread out and the edges a^1 turned up at right angles to the web on the line $x-y$, so as to form as it were a trough. The foil tongues now constitute angle-pieces and serve to retain the edges a^1 in the upright position. The wet cloth c is next laid in the bed of the "trough," whereupon the upright edges are folded down upon the cloth c in the manner shown at 2 on the bottom part and

all along the top part of the bandage (Fig. 1). With such a bandage it is obviously impossible for the wet cloth c to shift, since the folded and stiffened edges a^1 of the wrapper 60 retain it in place. Nor is there any danger of the patient catching a chill; for as the marginal portions of the finished bandage, owing to the overlapping edges a^1 , are thicker than the central portion, they fit tightly 65 against the part of the body to which the bandage is applied and effectually prevent air having access to the wet cloth c , which is completely shut in by them. In other words, whereas in prior bandages the space which 70 exists between each edge of the wrapper and the skin of the patient is occupied by the respective edge of the wet cloth, in the new bandage the equivalent space is filled up by the thickened marginal portion of the wrap- 75 per itself. The actual cloth-receiving portion of the wrapper may conveniently be made with a long plain-web extension (a portion of which is shown at 3), which in applying the bandage is wound over the rest of the 80 wrapper, thus holding the whole firmly together.

In the modification illustrated in Fig. 2, the wrapper a is furnished with thickened edges a^2 from which extend the foil tongues 85 b . With this bandage the foil tongues must first be turned up so as to project vertically upward from the web, the wet cloth c is then laid flat upon the bed presented by the central portion of the wrapper a between the 90 thickened edges a^2 , whereupon the foil tongues are folded down upon the cloth c again to hold it in place while the bandage is being applied. The thick edges a^2 constitute a substitute for the folded edges a^1 of 95 the bandage shown in Fig. 1. If some care is employed in applying the bandage, the foil tongues b may be altogether dispensed with in this modification, since their office is, as already explained, but a temporary one; 100 when once the bandage has actually been applied, it is really the thickened edges a^2 which prevent shifting of the cloth. It is obvious that, if desired, in addition to the wet cloth c , a rubber, oil-cloth or other non-porous layer may be used with the wrapper. 105

Having thus described my invention, I declare that what I claim as new and desire to secure by Letters Patent is—

1. A bandage, comprising a cloth adapted 110 to be wetted, a wrapper covering the back of the same and having marginal portions

which confine the edges of the cloth, and metal foil tongues attached to said marginal portions of the wrapper and adapted to fold down upon the cloth, substantially as described.

2. A bandage, comprising a cloth adapted to be wetted, a wrapper covering the back of the same and having marginal portions which are adapted to fold down upon the

edges of the cloth, and metal foil tongues attached to said marginal portions of the wrapper, substantially as described.

In testimony whereof I affix my signature in presence of two witnesses.

DAVID SARASON.
